UNITED STATES PATENT OFFICE.

ADRIAN J. NEERKEN, OF DETROIT, MICHIGAN, ASSIGNOR TO PACKARD MOTOR CAR COMPANY, OF DETROIT, MICHIGAN, A CORPORATION OF MICHIGAN.

DESIGN FOR A LAMP.

42,697.

Specification for Design.

Patented July 2, 1912.

Application filed March 28, 1912. Serial No. 686,949. Term of patent 7 years.

To all whom it may concern:

Be it known that I, ADRIAN J. NEERKEN, a citizen of the United States, residing at Detroit, in the county of Wayne and State of Michigan, have invented a new, original, and ornamental Design for a Lamp, of which the following is a specification, reference being had to the accompanying drawing, forming part thereof, in which—

Fig. 2 is a view of the other side of the lamp; and Fig. 3 is a front view.

I claim:

The ornamental design for a lamp as shown.

ADRIAN J. NEERKEN.
